UNITED STATES PATENT OFFICE.

MICHAEL SCHIANO, OF AUBURN, VICTORIA, AUSTRALIA.

COMBINATION OPENING DEVICE FOR BOTTLES.

1,367,432.

Specification of Letters Patent.

Patented Feb. 1, 1921.

Application filed March 12, 1920. Serial No. 365,288.

To all whom it may concern:

Be it known that I, MICHAEL SCHIANO, a subject of the King of Italy, residing at No. 13 Victoria road, Auburn, in the State 5 of Victoria, Commonwealth of Australia, have invented new and useful Improvements in Combination Opening Devices for Bottles, of which the following is a specification.

10 This invention relates to a combination opening device for bottles and provided with means for removing metal capsules, unscrewing wooden stoppers and for forcing in glass balls or marbles.

15 In the accompanying drawings—

Figure 1 is a sectional side elevation, and Fig. 2 a front elevation of the opening device, and

20 Fig. 3 is a side sectional elevation of a modified form of opening device, and

Fig. 4 a front elevation of Fig. 3.

25 The device as illustrated in Figs. 1 and 2 consists of an L shaped metal bracket or angle iron, the short arm E of which is holed to be screwed near the edge of a counter or table, and when so positioned the arm E projects backward from the stem or long arm A as shown. The device is bent at its upper end and formed into a hook B, the edge of which is tapered or sharpened to engage the corrugated edge of a metal capsule. In order to remove the capsule the latter is placed under the hook B and when the bottle is jerked or pulled 30 down the capsule is forced or levered off.

35 A vertical slot or hole C is punched or cast in the stem or arm A, and is of sufficient length and width to receive the head of a wooden stopper or plug of the type 40 which has a threaded stem and rubber washer and screws tightly into the internally threaded neck of bottle. To remove the stopper or plug the head of the latter is inserted in the slot C, and it is only necessary to twist or turn the bottle to unscrew same.

45 D is a conical pin projecting from the arm A of bracket and which is suitably riveted to same, said pin having a shank to receive 50 a rubber washer or pad d which relieves the jar of the impact and prevents the neck of the bottle from being broken when it is forced against the pin.

The slightly modified form of opening 55 device shown in Figs. 3 and 4 is specially adapted to be placed under the ledge of a

counter, the stem or arm F of which modified opener is also formed into a hook G or capsule remover. The stem is bent to form a U shaped recess H, the inner end of 60 which being slanted and holed to enable the device to be screwed to the side of the under frame of counter or table, and adapted to receive and grip the head of a wooden stopper which when turned is unscrewed from 65 the bottle as before described.

The glass ball or marble is forced in by means of a prong I which is punched or stamped out leaving two legs over which a rubber tube J is secured to present a soft 70 and yielding surface to the neck of the bottle.

It is obvious that either form of opening device may be slightly modified or altered without departing from the spirit or scope 75 of this invention. Thus the vertical slot may be horizontal and below the conical pin or other slight alterations as desired.

Having now described my invention what I claim as new and desire to secure by Letters Patent is:—

1. A device of the character substantially as described comprising, a bracket, a bottle cap engaging hook formed by an end of said bracket, a seat bent from the other 85 end of said bracket and extending from the hook side thereof, and a base formed from the intermediate portion of said bracket and extending in a direction opposite to and away from the hook side thereof, said base 90 forming a seat in and on the intermediate portion of said bracket and so arranged with respect to said hook as to permit normal, uninterrupted operation thereof.

2. In a bottle opening device of the character substantially as described, the combination of a bottle closure engaging means with, seats formed in and on the body portion of the device and adapted to receive and have secured thereto attachment devices, 100 said seats so positioned and arranged with respect to said closure engaging means as to permit of the normal, uninterrupted operation thereof.

In testimony whereof I have signed my 105 name to this specification in the presence of two subscribing witnesses.

MICHAEL SCHIANO.
